ELECTRODEPOSITION OF ZINC

Karl Kaizik, Breslau, Germany, assignor to the
firm Georg Von Giesche's Erben, Breslau, Ger-
many

Application August 8, 1932, Serial No. 627,961
In Germany April 21, 1931

8 Claims. (Cl. 204—5)

In the electrolysis of aqueous zinc solutions there are disadvantages which are removed by the present invention.

In order to attract sufficient zinc ions to the cathodes, large distances of about 5 cm. between the electrodes were first used so that the volume of the bath became large. If smaller distances, down to 2 cm. were used, it was necessary to mix the liquid by pumping, which required a considerable expenditure of energy. In the first case there is also the disadvantage of high current consumption. In both cases when zinc lyes containing manganese salts were used, a loose deposit of manganese dioxide was formed on the anodes, which constantly dropped off, thereby leading to short circuits and making it impossible to protect the anode against being eaten away as its surface was continually exposed again.

All these drawbacks are avoided according to the invention by adopting in the electrolysis of aqueous zinc lyes a step which has already been employed in the electrolytic decomposition of water and in making bleaching lyes, in which cases, in contradistinction to zinc electrolysis, no electrolyte is added or removed and it is not necessary to lift the cathodes out regularly. This step consists in providing the cells with insertions running at right angles to the surfaces of the electrodes. With two such insertions in a cell the latter is divided into three chambers, the electrodes being in the middle chamber. The gas bubbles rising from the electrodes draw the electrolyte from the two side chambers so that it passes under the insertions into the electrode chamber, rises between the electrodes and flows back to the side chambers over the insertions. It has already been proposed to provide these insertions with grooves for securing the bipolar electrodes.

In order to apply this step to zinc electrolysis with insoluble anodes in which monopolar electrodes are employed, the following procedure is adopted:

The electrode chamber is separated at the sides from the rest of the bath by suitable devices of acid resisting material. These devices consist, for example, of glass members of suitable shape which are secured to the anodes, or of suitable insertions in the bath in which the electrodes are pushed. Its upper end is below the surface of the bath so that the electrolyte which becomes specifically lighter on account of gas bubbles and heating is constrained to rise between the electrodes and can only pass over into the

free bath chambers at the sides at these points. This invention thus uses the upward drive due to heating and gas bubbles for obtaining a uniform and intensive mixing of the whole content of the bath and this causes a constant zinc and acid concentration to be maintained in all parts of the bath. This circulation is assisted by the cooling devices being arranged between lateral limitation of the electrode chamber and bath wall, whereby the electrolyte arriving there is cooled and becomes specifically heavier and therefore sinks.

In carrying out this method of operation, since fluctuations in concentration are avoided, a more compact, more adherent and harder manganese dioxide coating is obtained which makes the anode to a large extent passive and prevents the lead anodes dissolving, so that the lead content of the cathode zinc remains considerably lower than that in an ordinary bath. The adhering manganese dioxide coating gives the further advantage that the distances between the electrodes can be reduced to a minimum without fear of short circuiting. The strong circulation of lye obtained according to the invention and the use of smaller distances between the electrodes makes the volume of the bath much smaller and enables the amount of energy required per unit zinc deposit to be considerably reduced. In addition, the precipitation of manganese dioxide from the electrolyte, after a smooth and solid covering of manganese dioxide has been obtained on the anode, is reduced to a fraction of that in baths with an electrode chamber which is open at the sides.

Further, the invention allows of the electrodes being drawn out very conveniently, if necessary in groups, it being possible to reduce the distance between the electrodes over the whole surface to 1½ cm. This causes a uniform distribution of current and a further saving in current.

A further important advantage of this method of operation lies in the elimination of pumping work when high current densities are employed. While with the usual methods, when high current densities are used, the electrolyte has to be mixed within the bath by continually pumping round the same electrolyte, when using the present invention the pumping is unnecessary. The addition of the neutral lye to each bath is effected by gravity from a common raised container for several series of baths.

It has also been found that the manganese coating is caused to adhere still more firmly if, when using the above-described arrangements,

perforated double anodes are employed for improving the circulation. The use of anodes perforated over the whole surface does not affect the mixing of the electrolyte in the electrode chamber if the holes have a cross-section of not more than 5 to 100 sq. mm. and run exactly perpendicular to the surface of the anode.

The mixing can be improved if, when unperforated anodes are employed, the anodes have 10 openings just below the surface of the bath, which enable the rising electrolyte to flow into the space between the two parts of the double anode.

When double anodes are employed, intermediate members can also be secured to two adjacent 15 anodes which form a double anode. The intermediate pieces then project on both sides of the anodes so as to form guides for the cathodes lying beside the anode.

Finally the intermediate members, when double anodes are employed, may be so constructed 20 that within each double anode, as well as beside it, a cathode comes to lie on each side and is guided by intermediate members.

In the accompanying drawings the invention is 25 illustrated diagrammatically and by way of example in a number of constructional forms. All the parts which are not essential to understanding the invention are omitted.

Figure 1 shows a general plan view and Figure 30 2 a corresponding cross-section. 1 is the wall of the cell with the electrolyte 2, the anodes 3 and the cathodes 4. 5 are the insertions provided according to the present invention.

According to Figure 3 these insertions reach to 35 the bottom of the cells and above the level of the liquid and have openings 6, 7 above and below to enable the liquid to circulate.

In Figure 4, 8 are cooling members arranged 40 outside the insertions 5, while in Figure 5 the cooling is effected by a space 9, through which cooling water flows, arranged outside the longitudinal walls of the cell.

In Figures 6 and 7 the insertions 5 have slots 10 in which the electrodes can slide. Figure 8 shows 45 the same arrangement for insertions projecting above the liquid.

Figures 9 and 10 show double anodes each having a cathode lying between its members, the 50 insertions, which are constructed as intermediate members, connecting together two corresponding anodes and not being found in the space between the pairs of anodes. According to Figure 10 the intermediate members have guides 10 for the cathodes.

In Figure 11 the intermediate members 5 lie 55 between two anodes not belonging to the same double anode and are extended at 11 so far beyond the anodes that they abut in front of the cathodes and form a guide 10 therefor.

According to Figure 12 the cathodes and their 60 guides are disposed within each pair of anodes

as well as between each two neighbouring pairs of anodes. In this case the intermediate members, as in Figure 11, can be carried by two anodes or may be divided into halves each carried by one anode.

Figures 13 and 14 show a double anode with 5 openings 12 which lie in its surface just below the surface of the liquid and serve for the liquid to pass through. Anodes perforated over the whole surface are not shown in the drawings because in this case the holes do not enter into the mode of operation here described.

Figure 15 shows a double anode of thin separate plates held together by reinforcements 13. These reinforcements may be of any desired construction.

I claim:

1. Apparatus for electro-deposition of zinc from aqueous solution containing manganese salts including lead anodes arranged in pairs to 20 form double anodes and insertions extending at right angles to the electrodes and connecting the members of each double anode.

2. Apparatus as claimed in claim 1, the insertions having slots for receiving a cathode.

3. Apparatus as claimed in claim 1, the insertions projecting beyond the anode on both sides and forming a guide for a cathode between two adjacent projections.

4. Apparatus as claimed in claim 1, the insertions having slots for receiving a cathode and projecting beyond the anode on both sides and forming a guide for a cathode between two adjacent projections.

5. Apparatus as claimed in claim 1, the double anodes having openings immediately below the surface of the bath for enabling the liquid to flow through the space in the interior of the double anode.

6. Apparatus as claimed in claim 1, the double anodes consisting of thin plates and reinforcing members holding the plates together.

7. A method of electrodeposition of zinc from aqueous solutions containing manganese salts, using lead plates, the electrodes being arranged in multiple groups, consisting in applying current to the electrodes whereby heat and gas are developed in the electrolyte causing the latter to flow upwardly in a plurality of streams between the electrodes, confining the upward flow of the electrolyte to the portion of the latter lying between the electrodes and thereby inducing downward flow of the portion of the electrolyte outside of the electrodes to produce and maintain complete circulation of the electrolyte.

8. In the method claimed in claim 7, cooling the electrolyte at the part of its circulatory path lying outside the electrodes, where the electrolyte is flowing downwards, for assisting the circulation of the electrolyte.

KARL KAIZIK.
